GRINDING MACHINE

Harry J. Shelton, Jr., Ladue, Mo., assignor to
Gruendler Crusher and Pulverizer Co., St. Louis,
Mo., a corporation of Missouri

Application September 12, 1949, Serial No. 115,250

5 Claims. (Cl. 241—38)

1

This invention relates in general to grinding machines and more particularly to certain new and useful improvements in garbage grinders.

It is the primary object of the present invention to provide a garbage grinder having an extremely large capacity, and being capable of disintegrating all types of garbage ranging from vegetable leaves to heavy roast bones, and is so constructed that none of the entrant material can be hurled upwardly and out of the grinder through the intake opening thereof.

It is a further object of the present invention to provide a garbage grinder having means for flushing the incoming garbage downwardly into the grinder cage to prevent clogging or choking of the intake.

It is an additional object of the present invention to provide a garbage grinder wherein the axis of the rotation of the grinding elements is perpendicular to the vertical axis of the intake opening.

It is a further object of the present invention to provide a garbage grinder which is fabricated of relatively few parts and which is durable and reliable in use.

With the above and other objects in view, my invention resides in the novel features of form, construction, arrangement, and combination of parts presently described and pointed out in the claims.

In the accompanying drawing:

Figure 1 is a front view of a garbage grinder constructed in accordance with and embodying the present invention;

Figures 2 and 3 are transverse sectional views taken along lines 2—2 and 3—3, respectively, of Figure 1; and

Figure 4 is a transverse sectional view taken along line 4—4 of Figure 3.

Referring now in more detail and by reference characters to the accompanying drawing, which illustrates the preferred embodiment of the present invention, A designates a garbage grinder comprising a unitary cast housing 1 provided at its upper end with an upwardly opening aperture 2, the margins of which are integrally provided with a peripheral flange 3 for conventional securing to a pipe, sink, waste hopper or the like (the latter not being shown).

The intake aperture 2 opens downwardly into a curved, downwardly extending passage 4, having a relatively short vertical portion 5 and curving outwardly therefrom, and thence rearwardly, in substantially C-shaped formation, whereby the central portion of the passage 4, as at 4', will be laterally disposed from the vertical axis of the

2

intake aperture 2. The bight portion of the passage 4 is reinforced by a web 6 integrally formed with the housing 1. Provided in the rearward wall of the passage 4, adjacent the throat portion 5, is an internally threaded aperture 7 for receiving the threaded end of a water pipe 8 connected to a conventional water source (not shown). Suitably secured, as by welding, to the inner face of the passage 4, just above the aperture 7, is a baffle plate 9 extending downwardly and outwardly beyond the aperture 7 for deflecting inflowing water over the bottom wall of the passage 4.

At its lower end, the passage 4 opens into a cylindrical, horizontally disposed grinder cage 10, the rearward end of which is provided with a removable end plate 11 suitably secured to the housing 1 by bolts 12. The bottom portion of the cage 10 communicates with a downwardly extending discharge chute 13, the side and forward portions of which converge into a discharge orifice 14 provided with a peripheral flange 15 for securing to a sewer or other discharge line (not shown).

The end plate 11 is provided with a centrally located aperture 16 through which extends a horizontal shaft 17 of a conventional electric motor 18 (fragmentarily indicated), the latter being mounted upon the end plate 11. The axis of rotation of said shaft 17 lies in the same perpendicular plane as the vertical axis of the intake opening 2. Mounted upon the shaft 17, within the aperture 16 of the end plate 11, is a packing gland 19 for preventing any substantial leakage of water along the shaft 17. The projecting end of the shaft 17 terminates approximately midway in the cage 10 and, keyed thereon, is a conical collar 20 abutting at its forward end against a retaining collar 21 secured upon the extremity of the shaft 17. Rigidly mounted upon the conical collar 20, and projecting radially therefrom at 180 degree intervals, are two arms 22, of increasing width and being provided on their outer ends with cutter blades 23, which are releasably held in place by bolts 24, provided in their leading edge with a plurality of spaced recesses or "nicks" 25. Removably disposed by bolts 26, in the walls of the chamber 10 at either side thereof in diametrically opposed position, are stationary cutter bars 27 having in their inwardly presented faces a plurality of recesses 28 which are offset from the recesses 25 of the cutter blades 23 (see Figure 3) to provide clearance, of relatively close tolerance, for the cutter blades 23 during operation.

Press fitted against the upper wall portion of

the cage 10 is a semi-cylindrical filler plate 29, for reducing to a desired minimum the clearance between the cutter blades 23 and the wall of the cage 10 for effective grinding action thereof. Provided in the lower half portion of the grinding chamber 10 is a semi-cylindrical, foraminous grinder screen 30 abutting at its upper margins against the under face of the cutter bars 27 and disposed in its bottom portion across the upper and of the discharge chute 13, said screen 30 being supported upon a shoulder 31 integrally formed in the walls of the cage 10.

In operation, the motor 18 is actuated to effect rotation of the rotors 22 and the water source is turned on to provide a flow through the pipe 8 and into the passage 4. The incoming water is deflected by the baffle 9 downwardly against the upwardly presented, curved face of the web 6, from whence it will be deflected against the face of the outwardly curved portion of the passage 4 and will thereon flow downwardly along the face thereof, into the cage 10. It will thus be seen that the baffle 9 and the curvature of the passage 4 prevent any water from being deflected upwardly into the intake aperture 2 and assure that such water will properly flush any surfaces to which garbage might normally adhere. Garbage is then dumped into the passage 4 through the intake aperture 2, and is sluiced downwardly along the curved passage 4 by the flushing water and carried thereby into the grinding chamber 10, wherein the garbage is pulverized by the cutter blades 23. The ground garbage will drop through the apertures in the screen 30 downwardly along the discharge chute 13 and outwardly through the orifice 14 for discharge into the sewer or into any suitable receptacle. During the grinding operation, relatively large garbage elements will be prevented from being carried completely around the grinding cage 10 by the cutter bars 27 and, thus, the garbage will be substantially maintained in either the upper or lower portion of the cage 10 until sufficiently pulverized for passage through the screen 30.

It will be noted that in the event garbage tends to accumulate faster at the entrance of the cage 10 than can be adequately accommodated therein, any back-wash occurring therefrom will be directed against the inner face of the forwardly curved portion of the passage 4, thus preventing any upward gushing through the intake aperture 2 into the face of the operator. This outstanding result is achieved by the combined effect of the horizontal disposition of the shaft 17 and the sinuous character of the passage 4. As stated above, there is no possibility of incoming garbage accumulating upon the walls of the passage 4 since the path traveled by the sluicing water assures that the more remote surfaces of the passage 4 will be continuously flushed.

It will also be obvious that the curvature of the passage 4 makes the cage 10 relatively inaccessible, so that an operator could not in any untoward manner get his hands caught in the rotating arms 22 should an attempt be made to disrupt manually any material piled up at the opening to the said cage 10.

It should be understood that changes and modifications in the form, construction, arrangement, and combination of the several parts of the garbage grinding machine may be made and substituted for those herein shown and described without departing from the nature and principle of my invention.

Having thus described my invention what I

claim and desire to secure by Letters Patent is:

1. A garbage grinder comprising a housing having a cylindrical grinder cage with a horizontally presented coaxial intake opening, a curved intake member having a vertically upwardly presented intake opening and a horizontally presented discharge opening coincident with the intake opening of the grinder cage, said member, between its openings, being provided with a substantially semi-circular passageway, the center line of which lies substantially within a vertical plane passing through the center line of the grinder cage, and grinding means disposed in said chamber.
- 15 2. A garbage grinder comprising a housing having a cylindrical grinder cage with a horizontally presented coaxial intake opening, a sinuous intake member having a vertically upwardly presented intake opening and a horizontally presented discharge opening coincident with the intake opening of the grinder cage, said member, between its openings, being provided with a substantially semi-circular passageway, the center line of which lies substantially within a vertical plane passing through the center line of the grinder cage, and water inlet means provided in said passage.
- 20 3. A garbage grinder comprising a housing having an upwardly presented intake aperture, said housing being further provided with a downwardly extending substantially semi-circular passage, water inlet means provided in said passage, a deflector member mounted in said passage spacedly from the water inlet means for directing water downwardly along the wall of said passage, a substantially cylindrical grinder cage having a coaxial intake opening directly communicating with the lower end of said passage, and rotary grinding means disposed in said chamber the center line of the passage and the center line of grinder means being disposed in substantially the same plane.
- 25 4. A garbage grinder comprising a housing having an upwardly presented intake opening, said housing being further provided with a downwardly extending substantially semi-circular passage, the central portion of said passage being laterally displaced from the vertical axis of the intake opening, water inlet means provided in said passage adjacent the intake opening, a deflector member mounted in said passage spacedly from the water inlet means for directing the flow of water flushingly along the wall of said passage, a substantially cylindrical grinder cage having a coaxial intake opening directly communicating with the lower end of said passage, and rotary grinding means mounted in said chamber the center line of the passage and the center line of the grinder means being disposed in substantially the same plane.
- 30 5. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 35 6. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 40 7. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 45 8. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 50 9. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 55 10. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 60 11. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 65 12. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 70 13. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 75 14. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 80 15. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 85 16. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 90 17. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation
- 95 18. A garbage grinder comprising a housing having an upwardly opening intake aperture, said housing being further provided with a downwardly extending sinuous intake passage, water inlet means provided in said passage adjacent the intake aperture for connection to a conventional source of water, a deflector member mounted in said passage spacedly from said water inlet means for directing incoming water flushingly along the wall of said intake passage, said housing being further provided with a cylindrical chamber communicating with the lower end of said intake passage, a shaft disposed in said chamber having its axis of rotation

in perpendicular relationship to the vertical axis of the intake opening, a conical collar mounted upon said shaft, arms mounted upon said conical collar and projecting radially therefrom, said arms having lateral edges presented toward the intake passage which lateral edges diverge outwardly in the provision of a somewhat conically shaped depression concentric with the intake opening for facilitating entrance of garbage into the interior of the cylindrical chamber, cutter blades adjustably mounted upon said arms, and means for rotating said shaft to effect disintegration of garbage carried into said chamber by the water.
